CLAIM

We claim the ornamental design for a vehicle body front, as shown and described.

DESCRIPTION

FIG. 1 is a perspective view of a vehicle body front showing our new design;

FIG. 2 is a front elevational view thereof;

FIG. 3 is a right side elevational view thereof;

FIG. 4 is a left side elevational view thereof; and,

FIG. 5 is a top plan view thereof.

The structural features depicted by means of broken lines in the drawing figures have been shown for the purpose of illustrating environmental structure only and form no part of the claimed design.
